(57) **CLAIM**

The ornamental design for a pet ottoman, as shown and described.

DESCRIPTION

FIG. 1 is a perspective view of a pet ottoman, showing my new design, illustrating a top component in a first, flat-top configuration;

FIG. 2 is a perspective view of the pet ottoman, illustrating the top component flipped over to a second, cushioned-top configuration;

FIG. 3 is a front elevational view of the pet ottoman of FIG. 2;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The cross-hatching in the drawings is illustrative of fabric material.
